FREDERICK W. BALDWIN, OF BADDECK, NOVA SCOTIA, CANADA.

TARGET.

Application filed May 14, 1921. Serial No. 469,724.

To all whom it may concern:

Be it known that I, FREDERICK W. BALDWIN, a subject of the King of Great Britain, and a resident of Baddeck, Nova Scotia, 5 Canada, have invented new and useful Improvements in Targets, which invention is fully set forth in the following specification.

The present invention is an improvement in targets particularly for use at sea.

10 Targets of the displacement type heretofore employed have frequently been of such size and construction as to retard the progress of the whole fleet when towed from the fleet anchorage to the firing range. This 15 involved substantial economic losses of every description; and one of the objects of the present invention is to provide a target which may be towed to the range, even by the smallest destroyer, without slowing up 20 the speed of the fleet or involving the expenditure by the destroyer that is towing the target of any undue power—and this even though the target, or indeed a string of them, may be from fifty to two hundred 25 feet in length. A further object is to provide a target so light, yet strong and rigid, that it may be towed at the normal speed of the towing vessel, thus providing gunnery practice at a moving target of a kind which 30 has heretofore been practically impossible.

It frequently is desirable to have target practice while the fleet is remote from land, and when it would be practically out of the question to have a target of suitable size 35 in tow for such a distance. With this consideration in mind, another object of the invention is to provide a construction such that targets of varying size, say from fifty to two hundred feet in length, or more, may 40 be expeditiously assembled at sea by the crew.

With these and other objects in view, as will hereinafter appear, the improved invention consists of a base of a truss structure 45 preferably constituted by a plurality of tetrahedral units, which construction affords great strength and rigidity combined with lightness. This base is supported on the surface of the water when at rest by a plurality of small boats or pontoons, and supported above the surface of the water

when in motion, as when the target is being towed, by a plurality of suitably arranged hydrofoil sets. The firing objective, as for example a canvas surface, is supported 55 above the base in any suitable way, as being secured between two upright masts or supports. Preferably, for the purpose of strength and stability, the base is of substantially T-shape and composed of two 60 trusses, each built up from the tetrahedral units, and one being arranged at substantially right angles to the other, the point of intersection of said trusses being near one end of one of them. 65

My invention provides a target which is light, but strong and rigid; easily assembled at sea to any desired size; readily repaired and so constituted as to sustain an enormous amount of gun fire; that is composed 70 of a few standard parts that can be compactly stowed away on board ship until needed and then readily assembled by unskilled labor; and which, compared with targets of the same size heretofore used, 75 are cheaper to build and repair.

A further object of the invention is to provide a novel connecting or corner device by which as many of the tetrahedral units as desired may be built up in a simple and expeditious manner.

Preferably, for a target of say fifty feet in length I employ a truss built up of tetrahedral units one cell in height, whereas for larger targets, say up to one hundred feet, 85 there is preferably employed a truss two cells high, and, for a target say two hundred feet in length I preferably employ a truss three cells or units high.

The improved target may be assembled 90 and in position for firing in a very short time, inasmuch as the building of the tetrahedral structures involves merely the assemblage of standard lengths of rods with the connecting pieces. After this is effected, 95 the boats or pontoons, the hydrofoil sets, and the firing objective may be secured to the trusses in any simple and effective manner, after which the target is ready for use as a stationary objective, when it is supported by the pontoons, or as a moving objective, when it is supported by the hydro-

foils, and is capable of being towed at high speed because of the minimum resistance offered by the small hydrofoil surfaces.

The invention will be more fully understood by reference to the accompanying drawings, illustrating several expressions of the inventive idea, and in which—

Fig. 1 is a side view of a target of small size of the fifty-foot type;

10 Fig. 2 is an end view of the same, Fig. 3 is a corresponding plan view, and Fig. 3^a is a transverse section on the line 3^a—3^a of Fig. 3;

15 Figs. 4, 5 and 6 are respectively a side view, plan view and end view of a larger target employing trusses, two tetrahedral cells or units in height, and Fig. 5^a is a transverse section on the line 5^a, 5^a, Fig. 5;

20 Fig. 7 is an end view of a two hundred foot target employing trusses three tetrahedral cells or units in height;

Fig. 8 is an elevation showing the means of connecting the rods constituting the tetrahedral units;

25 Fig. 9 is a cross-sectional view showing the means of connecting said rods with the connecting or corner device;

30 Fig. 10 is an elevational view of one of said connecting or corner devices; and

35 Fig. 11 is a perspective view of one of the tetrahedral cells or units showing the improved connecting or corner device at each point of intersection of the rods.

Referring to the drawings, wherein like reference numerals indicate like parts, and particularly to Figs. 1-3 and 8-11, inclusive, 12 indicates a longitudinal truss constituted by a plurality of tetrahedral units such as illustrated in Fig. 11, and 13 indicates a second truss built up at a right angle to the first truss near one end thereof. The tetrahedral units of which the trusses are composed are built up of rods of uniform length and size which are secured together by connecting or corner pieces 14. As illustrated in Fig. 11, each tetrahedral unit is composed of six rods 15, 16, 17, 18, 19 and 20, with corner pieces arranged at the intersections of the rods. Preferably, the 50 rods are of steel-tubing, four feet in length by 1 $\frac{1}{2}$ " in diameter, with $\frac{1}{16}$ " walls, and the connecting or corner pieces are preferably castings made of duralium or drilled-out steel-castings.

55 Each corner piece is provided with a plurality of projections 21 so that the tetrahedral units may be extended in any direction. As clearly shown in Figs. 9 and 10, the rods 15-20, inclusive, are preferably 60 connected to the corner pieces 14 by means of sleeves 22, each of which passes over a projection 21. One end of the rod projects into the sleeve until it abuts the end of said projection. The projections 21, like the 65 sleeves 22 and the rods, are provided with

perforations 21^a, and pins 23 pass through said perforations which will register when the parts are assembled as illustrated in Fig. 9. The parts are fixed in the position illustrated in said figure by any suitable means 24. This construction permits of the ready and efficient assemblage of the parts without the use of any screw-threaded or other complicated connecting parts which might readily get out of order or be difficult to manipulate.

70 The longitudinal truss 12 illustrated in Figs. 1, 2 and 3 is one tetrahedral unit in height, and the same is true of the transverse truss 13. At that end of this longitudinal truss 12 remote from the truss 13 is arranged, in the medial fore and aft line of said truss 12, a float or pontoon 25. This pontoon is preferably of the uniform type used on seaplanes. Similar pontoons 26, 27 80 are carried on the under side of the truss 13, one being mounted on each side of the medial fore and aft line of the truss 12. Adjacent the pontoon 25, and suitably secured to the truss 12 by any desired connection, is 90 a pair of hydrofoil sets 28 and 29; and adjacent each of the pontoons 26 and 27 is suitably mounted a set of hydrofoils 30 and 31. For the purpose of stability, the hydrofoil surfaces of these sets are arranged at 95 dihedral angles.

A firing objective 32, for example the usual canvas target, is carried by the base in any desired manner. As here shown, two masts or supports 33 and 34 project upwardly from the trusses 12 and 13, and the firing objective 32 is carried between them. These masts or supports are provided with bracing wires 35, 36 and 37.

100 It will be understood that, when the target is at rest, the same is supported by the pontoons, and when the target is in motion, as when it is being towed, the same will be supported on the hydrofoil sets. In this latter condition, the pontoons and the trusses 110 are carried above the surface of the water, and accordingly the resistance to the movement of the target will be reduced to a minimum because only the hydrofoil blades will pass through the water. For this reason, a 115 small boat can tow the fifty-foot target, such as is illustrated in Figs. 1, 2 and 3, and a destroyer can tow a very large target or a string of moderate sized targets without consuming enough horsepower to materially 120 reduce her speed.

Types of these larger sized targets are illustrated in Figs. 4, 5 and 6, wherein is shown a target of say one hundred feet in length, and Fig. 7 wherein is shown the construction of a target two hundred feet in length.

125 Referring to Figs. 4, 5 and 6, it will be observed that the longitudinal truss 12 is in this embodiment of a height of two tetra- 130

hedral units A and B. The same is true of the transverse truss 13. Aside from the increased size and strength of the trusses, the construction of the hundred-foot target may 5 be the same, so far as number and positioning of the hydrofoil sets and pontoons and the firing objective are concerned, as in the fifty-foot type.

In Fig. 7 there is illustrated the construction for a target of say two hundred feet 10 in length. In this embodiment the trusses 12 and 13 are each three tetrahedral units high, indicated by the letters A, B and E. In addition, the hydrofoil sets 30 and 31 at 15 each extremity of the truss 13 are preferably duplicated, as indicated at 30' and 31', and the pontoons 26 and 27 near each extremity of said truss 13 are preferably duplicated, as indicated at 26' and 27'.

20 It will be observed that the present invention obviates the necessity for the employment of the old displacement type of target which was difficult to tow and which consumed enormous horsepower at present speeds which is something over thirty knots per hour; and that, by the use of the present invention, targets of any desired size may be readily and simply assembled and towed with the minimum expenditure of horsepower. The advantage is emphasized that, by the use of the present invention, a target is provided which can be moved rapidly through the water at substantially the normal speed of the towing craft, and that these 35 targets may be built up to substantially the length of a war vessel of the dreadnought type and towed at substantially the normal speed of said vessel, thus affording gunnery practice of a kind which has heretofore been practically impossible. When, added to this, it is borne in mind that the target is built of standard parts that can be readily and expeditiously assembled to construct a target of any desired size, that its 40 assembly and repair may be made at sea, that the tetrahedral trusses will stand an enormous amount of gun fire without destruction and that the target, by reason of its "knock-down" character, may be disassembled and 45 compactly stowed away aboard ship until the need arises, it will be appreciated that the present invention is a most effective addition to naval training. Further, the provision of a T-shaped base constituted by two 50 trusses built up of tetrahedral units, which trusses connect the pontoons and hydrofoil sets, affords a construction which embodies to the maximum degree the characteristics of lightness, strength, rigidity and stability. 55 If desired, the fore and aft truss may be provided with a cloth-covering which could be laced on the sections in order to reduce the air resistance of the various members of the truss.

60 It will be understood that in the larger

targets, as of the one hundred foot type, the firing objective may be secured directly to the base or tetrahedral structure, thus avoiding the necessity of vertical masts.

While, for the purpose of clearness, several embodiments of the inventive idea have been herein shown and described in detail, it is to be understood that the invention is not limited to these structures but that the inventive idea is susceptible of various mechanical expressions within the limits of the appended claims.

What is claimed is:—

1. In a target, the combination of a base or support constituted by a series of connected tetrahedral units, a plurality of float structures carried thereby for supporting said base or support when at rest, a plurality of hydrofoil sets for supporting said base or support when the target is in motion, and a firing objective carried above said base or support.

2. In a target, the combination of a base or support constituted by a plurality of connected tetrahedral units, a plurality of hydrofoil sets secured to the under side of said base or support and supporting the same when the target is in motion, means secured to said base or support for supporting the same when at rest, and a firing objective carried above said base or support.

3. In a target, the combination of a base or support constituted by a plurality of connected tetrahedral units, a plurality of float members secured to said base or support and supporting the same when the target is at rest, means secured to said base or support for supporting the same when the target is in motion, and a firing objective carried above said base or support.

4. In a target, the combination of a base or support constituted by a plurality of connected tetrahedral units arranged in two series one at right angles and rigidly connected to the other, a hydrofoil set carried near 110 one extremity of one series and near each extremity of the other series to support the target when in motion, and a firing objective carried by said base or support.

5. In a target, the combination of a base or support constituted by a plurality of connected tetrahedral units arranged in two series one at right angles to the other, a hydrofoil set carried near one extremity of one series and near each extremity of the other series to support the target when in motion, said hydrofoil sets being arranged at dihedral angles, means secured to said base or support for supporting the same when at rest, and a firing objective carried by said 125 base or support.

6. In a target, the combination of a base or support constituted by a plurality of connected tetrahedral units one above the other, a firing objective arranged above said base,

means secured to said base or support for supporting the same when the target is at rest, and a plurality of hydrofoil sets connected to the under side of said base and 5 supporting the same when the target is in motion.

7. In a knock-down target, the combination of a truss constituted by tetrahedral units made up of rods of uniform length 10 connected by corner pieces, hydrofoil sets connected by said truss and supporting the same when the target is in motion, means secured to said truss for supporting the same when at rest, and a firing objective carried by said truss.

8. In combination, a target comprising a plurality of hydrofoil sets, a truss connecting said hydrofoil sets, means secured to said truss for supporting the same when at rest, 20 and a firing objective carried by said truss, said elements being adapted for ready assemblage and disassemblage.

9. In combination, a knock-down target comprising a plurality of pontoons and hydrofoil sets, trusses connecting said pontoons and hydrofoil sets, and a firing objective carried by said trusses, said elements being adapted for ready assemblage and disassemblage.

30 10. In a target, the combination of a longitudinal truss, a hydrofoil set mounted in the medial fore and aft line thereof, a second truss arranged at substantially right angles to said first truss, and rigidly connected thereto, a pair of hydrofoil sets carried by said second truss and arranged one on each side of the medial fore and aft line of said target, said hydrofoil sets extending downwardly and outwardly from the truss structure, and a firing objective carried by said trusses.

11. In a target, the combination of a longitudinal truss, a pontoon mounted in the medial fore and aft line thereof, a second truss arranged at substantially right angles to said first truss, a pair of pontoons carried by said second truss and arranged one on each side of the medial fore and aft line of said target, hydrofoil sets arranged at dihedral angles, and a firing objective carried by said trusses.

12. In a target, the combination of a longitudinal truss, a pontoon and a hydrofoil set mounted in the medial fore and aft line thereof, a second truss arranged at substantially right angles to said first truss, a pair of pontoons and hydrofoil sets carried by said second truss and arranged one on each side of the medial fore and aft line of said target, said hydrofoil sets extending downwardly and outwardly from the truss structure, and a firing objective carried by said trusses.

13. In a target, the combination of a T-shaped truss constituted by connected tetra-

hedral cells or units, a set of hydrofoils carried by said truss near each extremity of the same and supporting said target when in motion, means carried by said truss to support the same when at rest, and a firing objective carried by said truss. 70

14. In a target, the combination of a T-shaped truss constituted by connected tetrahedral cells or units, a pontoon carried by said truss near each extremity of the same 75 and supporting said target when at rest, and a firing objective carried by said truss.

15. In a target, the combination of a T-shaped truss constituted by connected tetrahedral cells or units, a set of hydrofoils carried by said truss near each extremity of the same and supporting said target when in motion, and a pontoon carried by said truss near each set of hydrofoils and supporting said target when at rest. 80

16. In a target, the combination of a skeleton base or support, a plurality of float structures carried thereby for supporting said base or support when at rest, a plurality of hydrofoil sets for supporting said base 90 or support when the target is in motion, and a firing objective carried by said base or support. 85

17. In a target, the combination of a truss constituted by units made up of rods of uniform length connected by corner pieces, hydrofoil sets connected by said truss and supporting the same when the target is in motion, means attached to said truss to support the same when at rest, and a firing objective 95 carried by said truss, said elements being detachably connected to form a knock-down structure. 100

18. In a target adapted to be towed at high speed through the water, the combination of 105 a base or support constituted by a longitudinal truss, a second truss arranged at substantially right angles to said first truss, pontoons secured to the under side of each of said trusses adjacent the opposite extremities thereof, hydrofoil sets secured to said base adjacent said pontoons, and a firing objective mounted on said base. 110

19. In a target adapted to be towed at high speed through the water, the combination of 115 a base or support constituted by a longitudinal truss formed of tetrahedral cells or units, a second truss formed of tetrahedral cells or units arranged substantially at right angles to said first truss, a plurality of float members secured to said base to support the same when at rest, a plurality of hydrofoil sets secured to said base to support the same in motion, and a firing objective mounted on said base. 120

20. In combination, a knock-down target adapted to be towed at high speed through the water comprising a truss structure formed of tetrahedral units, a plurality of hydrofoil sets secured to said truss struc- 125 130

ture and supporting the same when the target is in motion, float members secured to said structure adjacent said hydrofoil sets, and a firing objective carried by said structure.

21. In a knock-down target adapted to be towed at high speed through the water, the combination of a truss constituted by units made up of rods of uniform length connect-

ed by corner pieces, hydrofoil sets secured to said truss adjacent the extremities thereof, pontoons secured to the truss adjacent said hydrofoil sets, and a firing objective carried by said truss.

In testimony whereof I have signed this 15 specification.

FREDERICK W. BALDWIN.
